[57] **CLAIM**

The ornamental design for a mobile stand for supporting a table top for office machine, as shown and described.

DESCRIPTION

FIG. 1 is a perspective view of a mobile stand for supporting a table top for office machines showing my new design;

FIG. 2 is a perspective view thereof taken from the side and end opposite to that shown in FIG. 1 and in a lowered position; and

FIG. 3 is an enlarged detailed perspective view of one of the telescoping support legs showing a longitudinally extending groove with a depth increasing toward the lower end of said leg.

FIG. I
